SHOE PRESS

Fred Dawson, West Roxbury, and John F. Smith,
Quincy, Mass., assignors to Compo Shoe Machinery Corporation, Boston, Mass., a corporation of Delaware

Application May 11, 1944, Serial No. 535,042

12 Claims. (Cl. 12—33)

This invention relates to shoe presses for use in the manufacture of shoes and relates more particularly to shoe presses in which outsoles are attached to lasted uppers by means of an adhesive.

In shoe presses of this type, the shoes are placed in, and removed from, the presses from the heel post ends thereof. The heel and toe posts have to be retracted to permit this insertion and removal, and in prior presses, the mechanisms for clamping and retracting the heel posts has blocked the vision of the operator of the presses in the loading of the shoes in the presses, and the mechanism for clamping and retracting the toe and heel posts, and for adjusting same, has required too much time and attention from the operators.

A feature of this invention resides in the provision of a shoe press in which the heel and toe posts are simultaneously actuated for clamping and retraction.

Another feature of the invention resides in a substantial reduction in the space previously required by the heel post actuating mechanism.

Another feature of the invention resides in the provision of means for quickly adjusting the heel post for clamping shoes having different depths in their heel portions.

Another feature of the invention resides in the provision of a last contacting surface on the heel post which automatically aligns itself when pressed against lasts having heel portions at different angles.

Another feature of the invention resides in the provision of an inflatable pad for pressing the outsoles of the shoes against the lasted uppers, which has its peripheral edges clamped to the base of the press.

An object of the invention is to reduce the space required in shoe presses by heel posts and their adjusting mechanisms.

Another object of the invention is to improve, in shoe presses, the heel and toe post clamping and retracting mechanisms.

The invention will now be described with reference to the drawings, of which:

Fig. 1 is a side elevation of a shoe press embodying this invention;

Fig. 2 is an end view with a portion of the base shown in section, of the shoe press of Fig. 1;

Fig. 3 is a view, in vertical section, of the heel and toe post clamping and retracting mechanisms in retracted positions;

Fig. 4 is a sectional view along the lines 4—4

of Fig. 5 and is a view similar to Fig. 3 but with the mechanisms in clamping positions;

Fig. 5 is a plan view looking downwardly upon the mechanism illustrated by Fig. 4;

Fig. 6 is a vertical section through the heel post taken substantially along lines 6—6 of Fig. 1, and

Fig. 7 is a plan view looking downwardly upon the press of Fig. 1.

Referring now to the drawings, the press base 10 has seated thereon, the inflatable pad 11 comprising as best illustrated by Fig. 2, the lower rubber member 12, the upper rubber member 13 and the leather cover 14. The rubber members 12 and 13 overlap at their peripheral edges which are clamped between the peripheral edges of the base 10 and the pad restraining member 15, which are drawn together by the clamping screws 16.

The pad restraining member 15 has the end portions 17 and 18 which extend over the heel and toe portions respectively of the pad 11 and which restrain upward movement of the heel and toe ends of the pad when same is inflated as will be described. The pad restraining member 15 is open between its sides and between its end portions 17 and 18 for permitting the upward movement of the sole contacting portion of the pad when it is inflated. The pad is adapted to be inflated through a valve assembly 9, the details of which are disclosed in the J. F. Smith U. S. Patent No. 2,152,366.

The overlapping portions of the rubber members 12 and 13 of the pad may be pre-sealed by pressure and heat, or otherwise secured together before being clamped as described. Prior pads were loosely held in recesses in the press bases by the air inflating valves and their periods of life were materially shortened by the failure of the stitching which held the upper and lower portions of the pads together, under the strains resulting from the flexing of the stitched areas.

The press includes the usual bow shaped, upper member 19 which is attached to the base 10 by the upright members 20. The enlarged portion 21 of the member 19 has a bore 22 which receives the sleeve 23 in which the heel post 24 reciprocates during its clamping and retracting movements.

The heel post 24 has the toothed rack 25 formed on one side and which is adapted to be engaged by the pawl 26 which holds the heel post in a selected position as will be described.

The pawl 26 is attached to the pivot shaft 27 which extends through the side walls 28 on the lower portion of the sleeve 23, and to one end

of which is attached the pawl release lever 29, and the other end of which is threaded to receive the locking nut 30. The spring 31 which extends in a bore in the pawl 26 and in the plunger 8, one end of which contacts the screw 32 which is threaded into one of the walls 28, presses the outer end of the pawl 26 downwardly for maintaining the inner end of the pawl in engagement with the rack 25 in the heel post 24.

The heel post 24 has a central bore 34 in which the spring 35 extends. The lower end of the spring 35 is attached to the screw 36 which is threaded into the heel post 24, and its upper end is attached to the washer 37 which overlaps the bore 22 in the enlarged portion 21 of the member 19. The spring 35 urges the heel post upwardly against the restraint of the pawl 26 engaging the rack 25. Lifting of the lever 29 disengages the pawl 26 from the rack 25 whereupon the spring 35 retracts the heel post 24 to its extreme upper position.

As may be appreciated, the heel post 24 may be easily adjusted for a particular size or depth of shoe by merely pulling the heel post 24 downwardly against the resistance of the spring 35 until the last contacting member 38 strikes the heel portion of a last 39 as illustrated by Fig. 1. The pawl 26 then engages the adjacent tooth of the rack 25 and maintains the heel post in the correct position.

It will also be noted that through the telescoping of the heel post 24 within the heel post supporting sleeve 23 and of the latter within the enlarged portion 21 of the bow member 19 of the press, the heel post when in its extreme upper position, does not extend above the upper surface of the member 19.

The lower end of the heel post 24 terminates in the member 42 which has a cylindrical inner surface and which has the side members 40 in which the slots 41 are formed. The last contacting member 38 has a cylindrical upper surface conformable with and in contact with the cylindrical surface of the member 42 and has a bore 43 in alignment with the slots 41 but of larger diameter, and in which are contained the spring 44 and the steel balls 45. The spring 44 pushes the balls 45 partially into the slots 41 which serve as seats for the balls. When the member 38 strikes a last, it rotates until its last contacting surface is in exact alignment with the flat upper surface of the heel portion of the last and the friction of the balls 45 against the slots 41 maintains its position.

The sleeve 23 has a lower portion 46 on the other side of the bore 34 from the walls 28, which has an inclined upper surface which contacts the conformably inclined lower surfaces of the extensions 47, of the member 48, which straddle the heel post 24 when it is in clamping position as illustrated by Figs. 1, 4, and 5. The member 48 has formed therein the slots 49 in which the inturned edges 50 of the plate 51 extend and which act as guideways during the horizontal reciprocating movement of the member 48 as will be described. The plate 51 is attached by the screws 52 to the lower surface of the bow member 19.

The slot 53 is formed in the inner surface of one of the extensions 47, parallel to its inclined lower surface and the pin 54 which is pressed into a hole formed in the sleeve 23 extends into this slot 53 and into a slot formed in the heel post 24. As the member 48 is reciprocated back and forth, the pin 54 riding in the slot 53 will

cause the heel post to be lowered and raised for clamping and retraction as will be described. The pin 54 being in engagement with the slot in the heel post also acts as a key to prevent rotation of the heel post.

The horizontal plate 55 which is attached by the screws 56 to the lower surface of the bow member 19, has formed in its lower surface a horizontally extending slot 57 in which the upper portion 58 of the wedge shaped reciprocating member 59 is fitted, and which serves as a guideway for the reciprocation of the member 59 as will be described.

The toe post 60 is slidably mounted in a vertically extending bore in the toe post support 62. The support 62 has in its upper portion, the spaced side members 61 which slidably engage the sides of the plate 55 whereby the toe post support 62 may be positioned along the plate 55 as will be described. The spring 63 around the toe post 60 in the support 62 urges the toe post upwardly. The toe post 60 has the usual resilient toe contacting pad 64 attached to its lower end.

The upper surface of the toe post 60 is inclined conformably with the inclined lower surface of the wedge shaped member 59 whereby the horizontal reciprocation of the member 59 causes the toe post to move downwardly against the restraint of the spring 63 for clamping the toe portion of the shoe, or permits the toe post to move upwardly under the influence of the spring 63 for retraction of the toe post.

The link 65 is pivoted at one end by the pivot pin 66 to the member 59 and is pivoted at its other end by the pivot pin 67 to one end of the lever 68. The lever 68 extends through a slot in the circular head 70 of the stud 71 and is attached thereto by the screw 69. The stud 71 extends through a bore in the member 72 which extends vertically downwardly from the bow member 19, and its other end 73 is reduced in diameter, is threaded and has attached thereto by the nut 74, the lever 75.

The other end of the lever 68 is attached by the pivot pin 76 to one end of the link 78, the other end of the link 78 being attached by the pivot pin 79 to the member 48.

Rotation of the lever 75 in a counterclockwise direction with respect to Figs. 1 and 5 of the drawings causes the above described links 65 and 78 to rotate and to move the members 48 and 59 horizontally inwardly towards each other to the positions illustrated by Fig. 3, at which time the spring 63 would cause the toe post 60 to be retracted, and the spring 35 would cause the heel post to be retracted.

Rotation of the lever 75 in a clockwise direction would cause the links 65 and 78 to rotate and to move the members 48 and 59 horizontally away from each other from the positions illustrated by Fig. 3 to the positions illustrated by Figs. 1, 4, and 5, causing the inclined lower surface of the member 59 to slide along the inclined upper surface of the toe post 60, causing the toe post to be moved downwardly to toe clamping position, and causing the inclined lower surfaces of the extensions 47 of the member 48 to slide along the inclined surface of the lower portion 46 of the sleeve 23, causing the heel post 24 to be moved downwardly through the engagement of the pawl 26 with its rack 25, to heel clamping position.

When the operating lever 16 is moved to lower the toe and heel posts as previously described, the links 65, 68 and 78 form a straight line and

act as locked toggles to prevent the wedge shaped members 48 and 59 from being moved when a shoe is pressed against the toe and heel posts.

For adjusting the toe post 60 for properly clamping a particular size of shoe, the upper side members 61 of the toe post support 62 are slideable along the plate 55 as described. The plate 55 has a plurality of horizontally aligned circular depressions 80 formed in one vertical side. The screw 77 is threaded into one of the side members 61 of the toe post support 62, in alignment with the plane of the axes of the depressions 80 so that its inner end may be fitted into one or another of the depressions 80 for anchoring the toe post support 62 in a selected position. Thus, the toe post support 62 may be moved to the right with respect to Fig. 1 of the drawings for receiving smaller sizes of shoes and may be moved to the left for receiving larger sizes of shoes.

As the toe post support 62 is moved along the plate 55 as described, the slideable contact of the lower inclined surface of the member 59, with the inclined upper surface of the toe post 60, causes the toe post to be raised when the toe post support 62 is moved to the left and to be lowered when the toe post support is moved to the right. Thus the toe post is automatically lowered and raised when it is adjusted longitudinally for smaller and larger sizes of shoes respectively.

The heel and toe posts may be clamped and retracted by the manual movement of the lever 75, or may be actuated for clamping and retraction, automatically, through movement of the conveyor in which the press illustrated is included. Such a conveyor is disclosed in the U. S. Patent No. 1,945,762. The means for the automatic clamping and retraction of the heel and toe posts will now be described.

The lever 82 has a slot 83 formed therein, and the pin 84 extends through this slot and through the extension 85 of the bow member 19. The roller 86 is rotatably mounted on the outer end of the lever 82 and is adapted to ride up the cam 87 during movement of the conveyor following deflation of the sole pressing pad as described in said patent. This causes the roller 86 and the lever 82 to move to the right with respect to Figs. 1, 4, and 5 of the drawings, and to move the member 88 which is attached to the other end of the lever 82 by the stud 89, to the right. The member 88 is formed on the lever 68 so that the movement of the lever 82 to the right as described, causes counter clockwise rotation of the lever 68. This causes the links 65 and 78 to be rotated from the positions illustrated by Figs. 1, 4, and 5 to the positions illustrated by Fig. 3 and causes the members 59 and 48 to be moved towards each other, permitting the spring 63 to retract the toe post 60, and the spring 35 to retract the heel post 24.

The lever 92 is pivoted at its center by the pin 93 which extends through the extension 85 of the bow member 19, and a slot at its lower end engages the pin 94 in the lever 82. The upper end of the lever 92 has the roller 95 rotatably attached thereto by the pin 96. The lever 97 actuated by the conveyor, is adapted to strike the roller 95 following the loading of another pair of shoes in the press and the starting of the conveyor, causing the lever 92 to move the lever 82 to the left with respect to Fig. 3 of the drawings and causing the lever 82 and the links 65, and 68 to be moved from the positions illus-

trated by Fig. 3 to the positions shown by Figs. 1, 4, and 5. This causes the member 59 to move the toe post 60, and the member 48 to move the heel post 24 downwardly to their clamping positions.

Assuming the start of an operation; the heel and toe posts retracted; the heel post in its extreme upward position, and the toe post in its extreme left hand position with respect to Fig. 1 of the drawings, the operator places a shoe in the press and rotates the lever 75 to place the heel and toe posts in clamping positions. He then moves the toe post 60 to the right until the pad 64 snugly contacts the toe of the shoe and then rotates the screw 77 into the nearest depression 80 in the plate 55, thus locking the toe post in its correct position for that particular size of shoe. He then moves the heel post 24 downwardly until the heel seat 38 snugly contacts the upper surface of the last 39, whereupon the pawl 26 under the influence of the spring 31, slips into mesh between the nearest teeth of the rack 25, thus locking the heel post in the correct position for that particular size of shoe.

The pad 11 is inflated and presses the sole against the shoe upper as is usual, it being understood that adhesive had previously been applied to the inner surface of the sole and to the corresponding surface of the shoe upper.

After the pad is deflated by movement of the conveyor as usual, the movement of the conveyor can cause the cam 87 automatically to strike the roller 86 and to affect the retraction of the heel and toe posts, if this is desired. Or alternatively, the conveyor may be stopped by the operator after deflation of the pad, and the retraction of the heel and toe posts affected by the rotation of the lever 75.

Following the placement of another shoe in the press, the heel and toe posts may be clamped by rotation of the hand lever 75 if this is desired or, alternatively, the conveyor may be started and the clamping of the heel and toe posts affected automatically by the pressure of the lever 97 against the roller 95 prior to the inflation of the pad.

While one embodiment of the invention has been described for the purpose of illustration, it should be understood that the invention is not limited to the exact apparatus and arrangement of apparatus illustrated, as modifications thereof may be suggested by those skilled in the art without departing from the essence of the invention.

What is claimed is:

1. In a shoe press, a press member, a heel post supporting member retractable within said press member, a heel post retractable within said supporting member, means for affixing said post at a selected position to said supporting member, and means including a toggle joint for moving said supporting member in and out of said press member for placing said heel post in retracting and clamping positions.

2. In a shoe press, a press member having a substantially vertical bore formed therein, a heel post supporting member having an upper portion in said bore, said supporting member having a substantially vertical bore formed therein, a heel post having its upper portion in said bore in said supporting member, said supporting member having a lower portion with an inclined upper surface, means including a member having an inclined lower surface formed complementary to said upper surface for moving said supporting mem-

ber downwardly from said press member, and means for affixing said heel post to said supporting member whereby the downward movement of said supporting member causes downward movement of said heel post.

3. In a shoe press, a press member having a substantially vertical bore formed therein; a heel post supporting member having its upper portion in said bore, said supporting member having a substantially vertical bore formed therein and having an enlarged lower portion having spaced walls straddling said heel post, a heel post having its upper portion in said bore in said supporting member, said walls having inclined upper surfaces, means including a member having an inclined lower surface formed complementary to said upper surfaces for moving said supporting member downwardly from said press member, and means for affixing said heel post to said supporting member whereby the downward movement of said supporting member causes downward movement of said heel post.

4. In a shoe press, a press member having a substantially vertical bore formed therein; a heel post supporting member having an upper portion in said bore, said supporting member having a substantially vertical bore formed therein, a heel post having its upper portion in said bore in said supporting member, said supporting member having a lower portion with an inclined upper surface, means including a member having an inclined lower surface formed complementary to said upper surface for moving said supporting member downwardly from said press member, means for affixing said heel post to said supporting member whereby the downward movement of said supporting member causes downward movement of said heel post, a toe post support having a bore formed thereon, a toe post supported in said bore in said toe post support, said toe post having an inclined upper surface, and means including a member having an inclined lower surface formed complementary to the said inclined surface of said toe post for moving said toe post downwardly concurrently with the downward movement of said heel post.

5. In a shoe press, a press member having a substantially vertical bore formed therein, a heel post supporting member having its upper portion in said bore, said supporting member having a substantially vertical bore formed therein and having an enlarged lower portion having spaced walls straddling said heel post, a heel post having its upper portion in said bore in said supporting member, said walls having inclined upper surfaces, means including a member having an inclined lower surface formed complementary to said upper surface for moving said supporting member downwardly from said press member, means for affixing said heel post to said supporting member whereby the downward movement of said supporting member causes downward movement of said heel post, a toe post support having a bore formed thereon, a toe post supported in said bore in said toe post support, said toe post having an inclined upper surface, and means including a member having an inclined lower surface formed complementary to the said inclined surface of said toe post for moving said toe post downwardly concurrently with the downward movement of said heel post.

6. In a shoe press, a press member having a substantially vertical bore formed therein, a heel post supporting member having an upper portion in said bore, said supporting member having a

substantially vertical bore formed therein, a heel post having its upper portion in said bore in said supporting member, said supporting member having a lower portion with an inclined upper surface, a reciprocating member having an inclined lower surface formed complementary to said upper surface and in contact with same, means supporting said reciprocating member for substantially horizontal reciprocation, resilient means urging said heel post upwardly, a toe post supporting member, a toe post supported for substantially vertical movement in said toe post supporting member, said toe post having an inclined upper surface, a second reciprocating member having an inclined lower surface formed complementary to said upper surface of said toe post, means supporting said last mentioned reciprocating member for substantially horizontal reciprocation, resilient means urging said toe post upwardly, and means for reciprocating said reciprocating members for lowering and raising said heel and toe posts.

7. In a shoe press, a press member having a substantially vertical bore formed therein, a heel post supporting member having an upper portion in said bore, said supporting member having a substantially vertical bore formed therein, a heel post having its upper portion in said bore in said supporting member, said supporting member having a lower portion having side walls straddling said heel post, said side walls having inclined upper surfaces, a reciprocating member having an inclined lower surface formed complementary to said upper surfaces and in contact with same, means supporting said reciprocating member for substantially horizontal reciprocation, resilient means urging said heel post upwardly, a toe post supporting member, a toe post supported for substantially vertical movement in said toe post supporting member, said toe post having an inclined lower surface formed complementary to said upper surface of said toe post, means supporting said last mentioned reciprocating member for substantially horizontal reciprocation, resilient means urging said toe post upwardly, and means for reciprocating said reciprocating members for lowering and raising said heel and toe posts.

8. In a shoe press supported for movement upon a conveyor, a press member having a substantially vertical bore formed therein, a heel post supporting member having an upper portion in said bore, said supporting member having a substantially vertical bore formed therein, a heel post having its upper portion in said bore in said supporting member, said supporting member having a lower portion with an inclined upper surface, a reciprocating member having an inclined lower surface formed complementary to said upper surface and in contact with same, means supporting said reciprocating member for substantially horizontal reciprocation, resilient means urging said heel post upwardly, a toe post supporting member, a toe post supported for substantially vertical movement in said toe post supporting member, said toe post having an inclined upper surface, a second reciprocating member having an inclined lower surface formed complementary to said upper surface of said toe post, means supporting said last mentioned reciprocating member for substantially horizontal reciprocation, resilient means urging said toe post upwardly, means including means actuated by movement of said conveyor for moving said reciprocating members for placing said heel and toe posts in clamping position.

tion, and means including means actuated by further movement of said conveyor for moving said reciprocating members for retracting said heel and toe posts.

9. In a shoe press, a press member having a substantially vertical bore formed therein, a heel post supporting member having an upper portion in said bore, said supporting member having a substantially vertical bore formed therein, a heel post having its upper portion in said bore in said supporting member, said supporting member having a lower portion having side walls straddling said heel post, said side walls having inclined upper surfaces, a reciprocating member having an inclined lower surface formed complementary to said upper surfaces and in contact with same, means supporting said reciprocating member for substantially horizontal reciprocation, a toe post supporting member, a toe post supported for substantially vertical movement in said toe post supporting member, said toe post having an inclined lower surface formed complementary to said upper surface of said toe post, means supporting said last mentioned reciprocating member for substantially horizontal reciprocation, and means for reciprocating said reciprocating members for lowering and raising said heel and toe posts.

10. In a shoe press supported for movement upon a conveyor, a press member having a substantially vertical bore formed therein, a heel post supporting member having an upper portion in said bore, said supporting member having a substantially vertical bore formed therein, a heel post having its upper portion in said bore in said supporting member, said supporting member having a lower portion having side walls straddling said heel post, said side walls having inclined upper surfaces, a reciprocating member having an inclined lower surface formed complementary to said upper surfaces, and in contact with same, means supporting said reciprocating member for substantially horizontal reciprocation, resilient means urging said heel post upwardly, a toe post supporting member, a toe post supported for substantially vertical movement in said toe post supporting member, said toe post having an inclined upper surface, a second reciprocating member having an inclined lower surface formed complementary to said upper surface of said toe post, means supporting said last mentioned reciprocating member for substantially horizontal reciprocation, resilient means urging said toe post

upwardly, means including means actuated by movement of said conveyor for moving said reciprocating members for placing said heel and toe posts in clamping position, and means including means actuated by further movement of said conveyor for moving said reciprocating members for retracting said heel and toe posts.

11. In a shoe press supported for movement upon a conveyor, a press member having a substantially vertical bore formed therein, a heel post supporting member having an upper portion in said bore, said supporting member having a substantially vertical bore formed therein, a heel post having its upper portion in said bore in said supporting member, said supporting member having a lower portion having side walls straddling said heel post, said side walls having inclined upper surfaces, a reciprocating member having an inclined lower surface formed complementary to said upper surfaces, and in contact with same, means supporting said reciprocating member for substantially horizontal reciprocation, a toe post supporting member, a toe post supported for substantially vertical movement in said toe post supporting member, said toe post having an inclined upper surface, a second reciprocating member having an inclined lower surface formed complementary to said upper surface of said toe post, means supporting said last mentioned reciprocating member for substantially horizontal reciprocation, means including means actuated by movement of said conveyor for moving said reciprocating members for placing said heel and toe posts in clamping positions, and means including means actuated by further movement of said conveyor for moving said reciprocating members for retracting said heel and toe posts.

12. In a shoe press, a press member, a heel post supporting member retractable within said press member, a heel post retractable within said supporting member, means for affixing said heel post at a selected position to said supporting member, a retractable toe post supported by said press member, means for pressing a shoe against said heel and toe posts, and means including a single operating lever for moving said supporting member and heel post and said toe post in unison from a retracted position to a shoe engaging position, and for preventing movement thereof when a shoe is pressed thereagainst.

FRED DAWSON.
JOHN F. SMITH.
